ELECTRIC SWITCH

Herman John Hammerly, New Britain, Conn., assignor to The Trumbull Electric Manufacturing Company, Plainville, Conn., a corporation of Connecticut

Application December 31, 1937, Serial No. 182,672

12 Claims. (Cl. 200—151)

My invention relates to knife blade switches and especially to those having hinged blades.

The main object is to protect the switch against damage from arcing by reducing the possibility of 5 arcing.

A special object is to provide simple and inexpensive means for this purpose.

Another object is to provide arc preventing means which can be readily removed for inspection 10 and replacement of the stationary switch contacts.

In its preferred form the invention contemplates an insulating base for supporting the stationary contacts and terminals and the movable 15 blades or switch members. This base is provided with upstanding walls with recesses or passages between them in which are mounted circuit terminals and stationary contacts in line with the switch blades.

20 An L-shaped guard is secured over these walls to partially enclose the switch contacts. These guards are slotted for the passage of the switch blades. I also preferably provide transverse barriers between the adjacent walls and separating 25 the stationary contacts from the binding posts of the line terminals. A ledge is also preferably provided along the foot of the guard.

The invention is illustrated as applied to an enclosed switch with quick-make and break 30 mechanism but the invention is not limited to such structures.

Fig. 1 is a front view of a switch embodying the preferred form of my invention in a switch box, the cover being open and parts broken away 35 and parts in section.

Fig. 2 is a vertical sectional view on the plane of the line 2—2 of Fig. 1.

Fig. 3 is a horizontal section of the switch mechanism on the plane of the line 3—3 of Fig. 1.

40 Fig. 4 is an exploded perspective view showing the principal parts of the invention.

Fig. 5 is a front view of a simpler form of the invention, parts being broken away and shown in section.

45 Fig. 6 is a vertical section on the plane of the line 6—6 of Fig. 5 showing the switch blade in the open circuit position.

Fig. 7 is a horizontal section on the plane of the line 7—7 of Fig. 5.

50 Fig. 8 is a perspective view of the guard member.

The switch base 9 is of insulating material and secured in the box 10 by screws 11, 11. The circuit terminals and binding posts 12 and 13 may 55 be of any suitable form. The switch contact jaws

14 are secured to the terminals 12. The switch blade member 15 is hinged to the post 16 which is connected to terminal 13.

The blades are actuated in any suitable manner for instance by the crank 17, handle 18 and 5 quick-make and break mechanism 19 of any suitable type. The base has side walls 20, 20 and intermediate walls 21, 21 (for a three wire system). Between adjacent walls are longitudinal passages or recesses 22, 22 in which the contacts 14 and 10 terminals 12 for each circuit are located so that they are separated from each other.

The transverse barriers 23 of insulation are detachably mounted in grooves 24 in adjacent walls and extend down to the terminal plates 15 between the binding posts and the respective stationary switch contacts. A transverse rib 25 extends across the base between the side walls and beneath the switch contacts. A guard member consisting of a horizontal top plate 26 and a vertical lower plate 27 is provided. This may be made of a single piece of insulating material in L-shaped section and have the top plate mounted on the outer surfaces of the walls or partitions 21, 21 and extend between the side walls 20, 20 25 so as to largely enclose the stationary contacts. This guard serves to hold the barriers 23 in place.

An additional top plate 28 is also preferably provided to span the side walls 20, 20. These top plates are secured in place by screws 29, 29 which 30 pass through them. The top plates are provided with slots 28' and 26' and the lower flange 27 has slots 27' so as to allow for the movement of the tips of the switch blades into and out of the 35 stationary contacts.

The enclosure of the stationary contacts in this manner serves to minimize the formation of arcs and to snuff out any which tend to form when the circuit is broken. The barriers 23 prevent 40 damage to the binding posts 15 and to the conductors. In case of need the guard members and barriers can be readily removed for inspection and repair.

In the form shown on the second sheet of drawings, the base 30 and the piece 31 carry the conducting parts and are suitably mounted in the box 32. The circuit terminals 33 and 34 are suitably secured to the insulation. The fuse clips 35 and 36 are also secured to the insulation in any suitable manner for receiving fuses such as 37. 45 50

The stationary contacts 38 are adapted to receive the movable ends or tips of the switch blade members 39 which are hinged to the posts 40 which in turn are connected to the fuse clips 35 in the usual manner.

The movable switch members are actuated in any suitable manner for instance by the crank 41, handle 42 and quick-make and break mechanism 43.

5 The base has side walls 44, 44 and the intermediate walls 45, 45 (for a three wire system) the block or base 30 is secured to the box by one or more screws such as 46. Between adjacent walls are recesses or passages 47 in which the 10 stationary contacts and the respective circuit terminals are mounted so that adjacent contacts are separated from each other and adjacent terminals are also separated from each other.

The guard 50 is of L-shaped section having a 15 top plate or flange 51 and a lower plate or flange 52 and is held in place removably on walls 45, 45 by one or more screws 53. The ends of the guard may also be supported in grooves 54 in the side walls. The walls 45 may have projections 55 20 extending between adjacent switch blades. The guard is slotted at 56 to fit the projections 55. A rib 57 projects from the base just below the edge 52 of the guard so as to afford additional support for the guard and to assist in stopping 25 arcs.

The guard is slotted at 58 in line with the paths 30 of the switch blades so as to provide a minimum clearance and thus tend to prevent the formation of arcs when the circuit is opened. These slots 35 may be formed in any suitable manner for instance by milling or cutting in the proper places. When the guard is in place it completely covers the stationary contacts but may be readily removed for inspection and replacement of the stationary contacts and the terminals.

I claim:

1. An electric switch having an insulating base with upstanding walls and longitudinal recesses containing terminals and switch contacts between the walls, hinged switch blades adapted to coact with the contacts and a slotted insulating guard of L-shaped cross section having one flange extending along the tops of the walls over the switch contacts and the other flange extending 45 toward the base and having its slots in line with the switch blades.

2. An electric knife blade switch having a base with upstanding walls and recesses containing switch contacts and terminals between the walls, 50 hinged switch blades adapted to coact with the contacts, a slotted insulating guard having one flange extending along the tops of the walls over the switch contacts and another flange extending toward the base and having its slots in line with the switch blades, and an abutment shoulder on the base 55 overlapping the lower edge of the guard.

3. An electric knife blade switch having an insulating base with upstanding walls and longitudinal recesses containing terminals and switch contacts between the walls, switch blades adapted to coact with the contacts, a slotted insulating guard having one flange extending along the tops of the walls over the switch contacts and another flange extending toward the base and having its slots in line with the switch blades, and transverse insulating members between adjacent walls and between the switch contacts and their respective terminals.

4. An electric knife blade switch having a base 70 with upstanding walls and recesses containing switch contacts and terminals between the walls, switch blades adapted to coact with the contacts, a slotted insulating guard of L-shaped cross section having one flange extending along the tops 75 of the walls over the switch contacts and the

other flange extending adjacent the base and having its slots in line with the switch blades, a shoulder extending between the guard and the switch blades and transverse insulating members between adjacent walls and between the switch contacts and their respective terminals. 5

5. An electric knife blade switch having an insulating base with upstanding walls and longitudinal recesses containing terminals and switch contacts between the walls, hinged switch 10 blades adapted to coact with the contacts, a slotted insulating guard of L-shaped cross section having one flange extending along the tops of the walls over the switch contacts and the other flange extending to the base and having its 15 slots in line with the switch blades, and transverse insulating members between the walls and between the switch contacts and their respective terminals.

6. An electric knife blade switch having an 20 insulating base with upstanding walls and recesses containing terminals and switch contacts between the walls, switch blades adapted to coact with the contacts, a slotted insulating guard of L-shaped cross section having one flange extending along the tops of the walls over the switch contacts and the other flange extending to the base and having its slots in line with the switch blades, transverse insulating members between the walls and between the switch contacts 25 and their respective terminals and an insulating top plate extending over all of the upstanding walls.

7. An electric knife blade switch having an insulating base with upstanding walls and longitudinal recesses containing switch contacts and terminals between the walls, switch blades adapted to coact with the contacts, a slotted insulating guard of L-shaped cross section having an upper flange extending over the switch contacts and 35 another flange extending toward the base and having its slots in line with the switch blades and a top plate extending over the upper flange of the guard and over the walls.

8. An electric switch having an insulating 45 base with upstanding walls and longitudinal recesses containing terminals and switch contacts between the walls, hinged switch blades adapted to coact with the contacts, a slotted insulating guard of L-shaped cross section having one flange extending over the switch contacts and the other flange extending toward the base and having its slots in line with the switch blades and an insulating abutment shoulder on the base 50 overlapping the lower edge of the guard. 55

9. An electric knife blade switch having an insulating base with integral upstanding walls and recesses containing switch contacts between the walls, hinged switch blades adapted to coact with the contacts and a slotted insulating guard of L-shaped cross section having one flange extending along the tops of the walls over the switch contacts and the other flange extending to the base and having its slots in line with the switch 60 blades. 65

10. An electric knife blade switch having an insulating base with upstanding walls and longitudinal recesses containing switch contacts and terminals between the walls, switch blades adapted to coact with the contacts and a slotted insulating guard of L-shaped cross section having one flange extending over the switch contacts and the other flange extending to the base and having its slots in line with the switch blades 70 75

and transverse barriers detachably held between adjacent walls over the terminals.

11. An electric knife blade switch having a base with upstanding insulating walls and longitudinal recesses containing switch contacts and terminals between the walls, switch blades adapted to coat with the contacts, a slotted insulating guard of L-shaped cross section having one flange extending along the tops of the walls over the switch contacts and the other flange extending toward the base and having its slots in line with the switch blades, an abutment shoulder on the base overlapping the lower edge of the guard and transverse insulating barriers detachably held between the contacts and the terminals.

12. An electric switch having a base with upstanding insulating walls and longitudinal recesses containing switch contacts and terminals between the walls, hinged switch blades adapted to coat with the contacts, a slotted insulating guard of L-shaped cross section having one flange extending along the tops of the walls over the switch contacts and the other flange extending to the base and having its slots in line with the switch blades, transverse insulating barriers between the terminals and the switch contacts and an abutment shoulder on the base overlapping the lower edge of the guard.

HERMAN JOHN HAMMERLY. 15
